UNITED STATES PATENT OFFICE.

ROBERT ALEXANDER BACHMANN, OF PITTSBURGH, PENNSYLVANIA.

SPRAYER.

1,397,851.

Specification of Letters Patent.

Patented Nov. 22, 1921.

Application filed November 29, 1920. Serial No. 427,040.

To all whom it may concern:

Be it known that I, ROBERT ALEXANDER BACHMANN, a citizen of the United States, and a resident of Pittsburgh, Pennsylvania, 5 United States of America, have invented certain new and useful Improvements in Sprayers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this 15 specification.

My invention relates to sprayers, more especially used for spraying insecticides, and the object of the invention is to make a self contained pump and reservoir of sheet metal 20 that can be made at small cost, is easily packed for shipping, whose parts projecting from the receptacle surfaces are protected by marginal flanges and which can be used in either a horizontal or vertical position. The 25 reservoir can have any cross sectional shape, such as square, circular, etc., but I prefer a triangular cross section as then no attached legs or brackets will be necessary when laying the sprayer down to maintain the liquid 30 pipes upright; at least one angle, the top angle can be curved to conform to the curvature of the pump barrel.

In order to allow the sprayer to be used in both horizontal and vertical positions I 35 employ a plurality of suction tubes at least two, terminating adjacent the air discharge orifice of the pump one of which extends to near the bottom at one end and the other of which extends to near the bottom at the 40 other end of the reservoir. The plurality of suction tubes are simultaneously acted upon by the air jet and one at least will promptly respond to the action of the jet as this tube is independent of any other and 45 dips into the liquid.

Referring to the drawing in which like parts are similarly designated and in which Figure 1 is a view showing one end of the sprayer, and

50 Fig. 2 is a vertical longitudinal section. In these drawings the reservoir 1 has secured to it triangular ends 2 and 3 by forming the joint in any well known manner as by lapping and bending and thus produces 55 marginal flanges 4. The flanges are wide

enough to protect the pump handle filler opening and spray pipes, when the sprayer is set on end.

At least the upper corner of the reservoir is rounded to conform to the cylindrical pump barrel 5 that is soldered at its ends to the two heads 2 and 3 of the can.

The can head 2 has a single perforation or air jet hole 6 and the head 3 has a hole 65 7 for the rod 8 of the pump plunger.

This plunger may be constructed in any manner desired and is here shown as a leather disk 9 held between two plates 10 and 11 through which the end of rod 8 70 passes and is swaged to hold the parts in position.

A handle 12 is secured on the opposite end of rod 8.

Adjacent the hole 6 are two liquid supply or spray pipes 13 and 14, both having short portions outside the can head 2 at the hole 6 and in spraying position. The pipe 13 extends downward to near the bottom of the can adjacent the can head 2 and 80 the pipe 14 extends through the can to near the bottom adjacent the can head 3.

Any suitable screw topped filling opening may be provided in any convenient position. Such a screw top opening 15 is 85 shown in the reservoir head 3.

By positioning the ends of a plurality of separate liquid supply pipes as 13 and 14 with their discharge ends in spraying position with relation to the air jet hole 6, I 90 always have one pipe capable of supplying liquid. There are no movable joints or valves and one pipe is not dependent upon the other for its operation, nor does one pipe tend to decrease the flow within the 95 other pipe as would be the case if the pipes communicated with one another, and especially if such connection were within the can.

The base of the triangular sprayer body 100 forms a stable seat. The flanges 4 protect the ends of pipes 13 and 14 that extend out of the reservoir, the screw top and pump handle, so that the sprayer may be stood on either end in shipping without injury to 105 these parts. The triangular shape facilitates packing.

One of the problems to be overcome in the type of sprayer in which the pump is inside of the reservoir is to prevent dripping from 110

the capillary tubes when the reservoir is full. This I do by placing the pump at the top of the reservoir, the object being to get the upper ends of the tubes 13 and 14 5 above the level of the liquid.

This is more easily attained with the triangularly shaped reservoir than with other shapes, as the walls of the reservoir fit around the pump barrel to a greater extent, 10 so that there will be less liquid at a level above the ends of the tubes when the reservoir is full.

I claim:

1. A sheet metal sprayer comprising a 15 triangular reservoir an air pump whose ends are formed by the ends of the reservoir and a liquid supply pipe in spraying relation to said pump.

2. A triangular sheet metal sprayer body 20 having an air pump inclosed within said body at the apex.

3. A sheet metal sprayer body having end flanges, an air pump within said body, a liquid supply pipe having one end thereof out- 25 side one of the can heads in spraying relation to said pump, a can filling closure and a pump handle, said pipe end, closure and handle lying within and protected by said flanges.

30 4. In a sprayer, an air pump having a single air jet discharge hole and a plurality of valveless liquid supply pipes of different

lengths terminating in spraying relation to said hole.

5. A sprayer having a triangular reservoir, 35 an air pump having a single air jet discharge hole near an apex of the reservoir, and two valveless liquid supply pipes terminating in spraying relation to said hole, one of said pipes extending within said reservoir at one 40 end of the reservoir and the other pipe extending within said reservoir to its opposite end.

6. In a sprayer, a triangular sheet metal reservoir, a cylindrical sheet metal pump 45 barrel within said reservoir, at its apex, said reservoir having its walls curved to conform to the curvature of the pump barrel.

7. A sprayer comprising a sheet metal, triangular reservoir, a cylindrical sheet metal 50 air pump barrel within and at the apex of said reservoir, which conforms to the shape of said barrel, a single discharge hole for said pump, a plurality of liquid supply pipes having their one ends in spraying relation 55 to said hole and their opposite ends extending to opposite ends of said reservoir, a reservoir closure, and a pump handle, said reservoir having end flanges of sufficient depth to protect said pipe ends, closure and handle. 60

In testimony that I claim the foregoing as my invention, I have signed my name hereto.

ROBERT ALEXANDER BACHMANN.
